PICTURE FRAME MACHINE

Stonio Varieur, New York, N. Y., assignor to Reliance Picture Frame Co. Inc., New York, N. Y., a corporation of New York

Application October 1, 1934, Serial No. 746,469

9 Claims. (Cl. 144—3)

The invention while especially adapted for picture frame machines may be employed or used in connection with frames of other sorts and other devices.

5 In making such frames a bead or frame member is cut so as to interfit with an adjacent member. The cut may be so made as to prepare for the adjacent members for interfitting at the same time. The adjacent members in the completed 10 frame are held together in appropriate position and this may be done by means of a nail or the like passed through both members. In order to facilitate this and at the same time to prevent or reduce the opportunity of splitting of one or 15 both members a hole frequently is bored in at least one member in a position to receive the fastening nail which going through the hole may pass into the other member and so attach the two members together. When this procedure has 20 been adopted it has been customary to make the cut by one machine and then by separate and independent means make the hole. It is a purpose of the present invention to provide a single machine for cutting and drilling or boring the hole. Preferably such a machine will operate to cut and 25 bore simultaneously although this may not be essential to the invention in all its aspects.

In the accompanying drawings showing embodiments of the invention Figure 1 is a side elevation of a machine for boring and cutting. Fig. 2 is a top plan view of such a machine, portions being broken away to better disclose details of the structure. Fig. 3 is a fragmentary horizontal section of a portion of a guide for the drilling means. Fig. 4 is a fragmentary vertical section of a portion of the structure associated with the drilling means. Fig. 5 is a side elevation of one of the cutting blades which cooperates with the drilling mechanism and Fig. 6 is a fragmentary 30 side elevation of an optional means for operating the cutting mechanism. Fig. 7 is a diagrammatic fragmentary plan showing the frame member in position in the machine.

The machine comprises a frame including members 10 on which is carried a bed or base plate 11 on which may be arranged the uncut molding or frame member to be operated on in a well known way. The character or number of knives or cutting devices employed is not essential to the 40 present invention, but in the particular machine shown a pair of cutting knives 12 and 13 are shown arranged at right angles and associated with suitable adjusting mechanism well known in the art. The knives 12 and 13 are carried by a frame member 14 which is capable of reciprocating

5 upward and downward in guideways against the tension of a spring 15 which normally tends to hold the knives in the upper position. In this upper position the frame member or molding X may be properly placed upon the bed 11 where it 10 may be held in position by a pressure shoe 45 preferably made of some soft resilient material so as not to injure the frame or molding. The pressure shoe 45 is held onto the molding X by a pressure block 16 carried by a pressure bar 17 15 suitably positioned on a portion of the main frame of the machine and normally held downward against the frame member X by a suitable spring 18. It will be understood that this pressure mechanism allows the machine to receive and 20 hold in a resilient manner moldings or frame members of various sizes and shapes. The molding X when inserted is placed and held on the base 11 and also against the backing member 19 supported on the main frame. As illustrated 25 particularly in Figs. 2 and 4 the backing member 19 has an aperture 20 in its adjacent one end of the molding X as cut which is adjacent the cutting knife 12. Through this aperture passes a 30 drill or boring device 21 which may be operated by any suitable mechanism here illustrated as an electric motor 22. The electric motor 22 is mounted on a bed 23 having downwardly depending runners 24 which engage guide rods 25 which extend rearwardly from brackets 26 depending 35 from some part of the main frame such as the bed member 11. The motor bed 23 at one or both sides may be provided with a suitable device such as the ball bearing 27 which is engaged by a pair of suitably inclined runways or guides 28 depending 40 from a lug 29 to which the spring is attached and which is carried by the vertically reciprocating carriage 14. It will be noted that the upper end of the spring 15 depends from a forwardly projecting rear member 30 of the main frame of 45 the machine. Extending from the forward frame member 10 to the rear frame member 30 is a bar 31 provided with a slot 32 through which passes a bolt 33 having at its end a wing nut 34 which carries and holds in place the bearing block 45 35 which acts as a guide for the lower ends of the guide bars 28. Depending from the reciprocating head 14 is shown an operating rod 36 which may be operated up and down by any suitable means. In Fig. 1 a cylinder 37 operated by hydraulic pressure is illustrated. In Fig. 6 an ordinary foot pedal 38 is illustrated for operating the rod 36.

When a piece of frame is placed in the machine as illustrated in Fig. 4 the rod 36 may be 55

depressed against the tension of the spring 15. This will bring the apparatus to the condition illustrated. Thus the knives 12 and 13 will descend and cut the frame member X and at the same time the lowering of the guides 28 will cause the motor 23 to be forced to the left in Fig. 1 thus bringing the drill 21 through the aperture 20 and into the frame member X. As illustrated in Fig. 2 the drill 21 is so placed that it passes through the frame member X at the point where the frame member is cut. Normally this would cause the drill to engage and be stopped by the cutting blade. In order that the drill may go entirely through the cut portion of the frame member an aperture 39 is provided in the face of the cutting knife 12. The lower cutting edge 40 of the cutting knife 12 is not disturbed but is left whole. It is thus possible to make a clean cut of the frame and begin the drilling before the cut is completed. By the time the drill 21 has advanced far enough to go through the frame member the blade 12 will have been lowered so that the drill 21 is not imbedded by the blade 12 but the aperture 39 is in position to receive the drill.

In the diagrammatic showing of Fig. 7 a strip of frame X is illustrated in position to be cut by the knives 12 and 13 and to be drilled by the drill 21 approaching from the side opposite from the knife 12.

Adjustments of various sorts in connection with the blades and cutting mechanism may be provided and the speed and extent of movement of the drill 21 may to some extent be varied by turning the guides 28 as on a pivot about the bolt or bearing 41 by which they are suspended from the lug 29. This adjustment of the guides 28 may be accomplished by movement of the guide block 35 as the bolt 33 is moved in the slot 32.

Various kinds of power may be employed to operate the machine it being understood that suitable force will be used to cut and drill the frame member X whatever its size or material. The same or different power may be applied to operate the drill and to operate the cutting mechanism. It is immaterial whether the current for the electric motor 23 illustrated is supplied by suitable means operated on the beginning or during the downward movement of the cutting device or whether the motor is continuously in operation. The current may be supplied to the motor 23 in any suitable manner. The drilling is performed during the advance movement of the motor and the rotation of the drill may be confined to that portion of the time or may be continuous.

It is to be understood that the size of the drill 21 is immaterial to the present invention. The operator may be relied upon to select and employ a suitable drill for whatever frame member is being treated. Likewise the invention may

be embodied in a wide variety of forms, sizes and structures other than those specifically illustrated.

I claim as my invention:

1. Means for cutting the end of a frame member, and means for drilling a hole in the member toward the cutting means while the cutting means is in cutting position.

2. Means for cutting the end of a frame member, and means for drilling a hole in the member directly at the cut portion as the cutting operation takes place.

3. Means for cutting the end of a frame member, and means for simultaneously drilling a hole in the member directly at the cut portion.

4. Means for cutting the end of a frame member, means for drilling a hole in the member toward the cutting means the cutting means being in cutting position and means associated with the cutting means for causing the drilling means to move toward the cutting means.

5. Means for cutting the end of a frame member including a reciprocable blade, means for reciprocating the blade, means for drilling a hole in the member at the cut portion, and means associated with the cutting means to cause the drilling means to advance toward the blade when it is reciprocated in cutting direction.

6. Means for cutting the end of a frame member including a reciprocable blade, means for reciprocating the blade, means for drilling a hole in the member at the cut portion, and means associated with the cutting means to cause the drilling means to advance toward the blade when it is reciprocated in cutting direction, the blade having a recess to allow the end of the cutting means to pass the cut edge of the member.

7. Means for cutting the end of a frame member including a reciprocable blade, means for reciprocating the blade, means for drilling a hole in the member at the cut portion, a guide for the drilling means, and a cam slot engaging the drilling means and attached to the cutting blade so that on movement of the cutting blade the drilling means moves on its guide at right angles to the movement of the cutting blade.

8. Means for cutting the end of a frame member including a reciprocable blade, means for reciprocating the blade, means for drilling a hole in the member at the cut portion, and means associated with the cutting means to cause the drilling means to advance toward the blade when it is reciprocated in cutting direction, the blade having a recess above the cutting edge to allow the end of the cutting means to pass the cut edge of the member.

9. Means for cutting the end of a frame member and means for cutting a hole in the member toward the cutting means, the cutting member being provided with means to allow the end of the cutting means to pass the cut edge of the member.

STONIO VARIEUR.
